UNITED STATES PATENT OFFICE.

ISIDORE KODISH, OF BROOKLYN, NEW YORK.

COMBINATION-PADLOCK.

1,331,933.

Specification of Letters Patent. Patented Feb. 24, 1920.

Application filed October 31, 1919. Serial No. 334,721.

To all whom it may concern:

Be it known that I, ISIDORE KODISH, a citizen of the United States, residing at Brooklyn, in the county of Kings and State 5 of New York, have invented new and useful Improvements in Combination-Padlocks, of which the following is a specification.

This invention relates to permutation locks, particularly to those of the padlock 10 variety, and has for its object the provision of a padlock having a slideable shackle and provided with a plurality of balls or other protuberances extending entirely around its edges, links and catch members being provided 15 within the body of the link connected with certain of the protuberances whereby upon pulling out certain protuberances in proper sequence, the shackle will be released.

An important object is the provision of a 20 lock of this character which is particularly designed to baffle any attempt of an unauthorized person to open the same so that the lock will be to all intents and purposes theft-proof as it is necessary to know which 25 protuberances to pull upon to effect releasing of the shackle.

An additional object is the provision of a lock of this character which will be simple 30 and inexpensive in manufacture, easy to operate when the secret of manipulation is known, which will be highly efficient and durable in use, and a general improvement in the art.

With the above and other objects and advantages in view, the invention consists in 35 the details of construction to be hereinafter more fully described and claimed, and illustrated in the accompanying drawings in which

40 Figure 1 is a front elevation of my lock, Fig. 2 is a side elevation thereof,

Fig. 3 is a longitudinal sectional view showing the parts in locked position, and

45 Fig. 4 is a similar view showing the parts in released position.

Referring more particularly to the drawings, I have shown the lock as comprising a casing 10 and a U-shaped shackle 11 having its arms 12 and 13 slideable through 50 holes 14 in the casing. Cast or secured upon the outer edges of the casing 10 are protuberances 15 which may be of any desired shape such as spherical, as shown. These 55 protuberances have no function other than to baffle any attempt of an unauthorized person to open the lock.

Disposed within the casing 10 is a bolt 16 with which engages one end of a coil spring 17 which extends through a bore 18 in the arm 12 of the shackle whereby the shackle 60 is normally urged into released position. The end of the arm 13 which extends into the casing is peripherally recessed, as shown at 19, to provide an arrow-like head 20. Pivoted within the casing 10, as shown at 21, 65 are latch arms 22 and 23 which are normally drawn together by a coil spring 24 and which have their freeends 25 engaging within the recess 19 for holding the shackle in locked position. Pivotedly connected with the 70 latch arm 23 is a stem 26 which extends slidably through the edge of the casing and which carries externally thereof a protuberance 27 identical with the protuberances 15. A coil spring 28 surrounds the stem 26 and 75 abuts against the arm 23 and the inner wall of the casing for normally holding the head 27 in retracted position. Pivotedly connected with the arm 22 is a link 29 which is pivotedly connected at its free end with a 80 lever 30, pivoted at 31, and having pivotally connected with its other end, as shown at 32, a stem 33, slideable through the edge of the casing and carrying a head 34 identical with the protuberances 15. Extending laterally 85 from the stem 33 is a projection 35 which normally engages one end 36 of an angle lever 37 pivoted at 38, within the casing. Pivotedly connected with the other arm of the angle lever 37, as shown at 39, is a link 90 40, which is in turn pivotally connected at 41, with one end of a lever 42 pivoted intermediate its ends, as shown at 43, within the casing. Pivotedly connected with the other end of the lever 42 is a stem 44 which extends 95 slidably through the opposite edge of the casing and which carries a head 45 identical with the protuberances 15. The normal or locked position of the parts is shown in Figs. 1, 2 and 3.

In the operation of the device when it is desired to open the lock, that is release the shackle 11 from engagement within the casing, it is first necessary that the operator grasp the head 45 and pull outwardly thereon, whereupon the lever 42 will rock upon its pivot 43, resulting in movement of the link 40 and swinging of the angle lever 37 upon its pivot 38. As this is done, the arm 36 of the angle lever 37 will be moved 100 out of engagement with the projection 35 on the stem 33. The operator then grasps

the heads 27 and 34 and pulls them outwardly, whereupon it will be apparent that the latch arms 22 and 23 will be moved apart against the resistance of the springs 24 and 5 28 so that the ends 25 will disengage the recess 19 in the arm 13 of the shackle. The spring 17 will then force the shackle away from the casing so as to permit disengagement of the shackle from any staple with 10 which it may be engaged. In order to re-lock the device, it is merely necessary that the shackle be pressed toward the casing so that the head 20 on the arm 13 of the shackle will pass through the hole 14 and 15 between the ends 25 of the arms 22 and 23.

From the foregoing description and a study of the drawings it will be apparent that I have thus provided an extremely simple and efficient combination padlock 20 which needs no key whatever and which will be very effective in preventing theft.

While I have shown and described the preferred embodiment of my invention, it is of course to be understood that I reserve 25 the right to make such changes in the form, construction, and arrangement of parts as will not depart from the spirit of the invention or the scope of the subjoined claims.

Having thus described my invention, I 30 claim:

1. A lock comprising a casing, a shackle extending into the casing and having the end of one arm formed with a retaining head, a pair of latch arms pivoted within 35 said casing and spring-pressed normally into engagement with said head, a stem connected with one latch arm and extending through the casing, a second stem slidable through the casing and connected with the 40 other latch arm, coöperating latch means normally holding said second named stem

against movement, a third stem connected with said latch means and extending through the casing, finger engaging heads on the stems exteriorly of the casing, and a plurality of protuberances on said casing corresponding in size and shape to said heads, outward pulling of said heads in proper sequence resulting in disengagement of said latch arms from the shackle. 45 50

2. A lock comprising a casing, a U-shaped shackle slidably associated with said casing and having one arm spring-pressed whereby the shackle will normally be disposed with its other arm out of the casing, a retaining head on said other arm of the shackle, a pair of latch arms engaging said head and normally spring-pressed together, a stem connected with one of said arms and extending slidably through the 60 casing, a support within the casing, a lever pivoted upon said support, a link pivotally connected with one end of said lever and with the other latch arm, a stem pivotally connected with the other end of said lever, 65 slidable through said casing, and provided with a lateral shoulder, an angle lever pivoted within said casing and having one end normally engaging said shoulder whereby to permit movement of said second named 70 stem, a lever pivoted within said casing and connected at one end with the other end of said angle lever, a third stem pivotally connected with the other end of said last named lever and extending slidably through the 75 casing, heads on the outer ends of said stems, and a plurality of protuberances on the casing identical in appearance with the heads.

In testimony whereof I affix my signature. 80

ISIDORE KODISH.
